(57) **CLAIM**

I claim the ornamental design for a jewelry toggle, as shown.

DESCRIPTION

FIG. 1 is a perspective view of a jewelry toggle.

FIG. 2 is a front elevation view thereof, where the front and back elevation views are identical.

FIG. 3 is a left side elevation view thereof, where the left and right side elevation views are identical.

FIG. 4 is a top plan view thereof; and,

FIG. 5 is bottom plan view thereof.
